(57) **CLAIM**

I claim the ornamental design for an improved clip and carry detachable eReader messenger bag, as shown and described.

DESCRIPTION

FIG. 1 is a left side elevation view of the clip and carry detachable e-Reader messenger bag as shown and described; the right side elevation view being a mirror image thereof; FIG. 2 is a front elevation view thereof; FIG. 3 is a rear elevation view thereof; FIG. 4 is a rear view shown in an open position; and, FIG. 5 is an environmental view thereof. The broken line/s showing the environment in FIG. 5 of the drawings is included for the purpose of illustrating only and forms no part of the claimed design.
